VACUUM RESPONSIVE DEVICE

Application filed October 10, 1928, Serial No. 311,685, and in Australia August 16, 1928

It is a recognized fact that a great deal of loss as well as inconvenience is occasioned through neglect to switch off the electrical current that is used for ignition purposes in connection with internal combustion engines after the engine is stopped. When the engine is used for propelling motor vehicles, the switch is generally located on the dash board, but even though it is conveniently situated for the driver it is, nevertheless, frequently forgotten.

The object of the present invention is to provide a switch whereby the electrical current can be switched on and off and a means for automatically operating it in such a manner that the electrical circuit is closed only whilst the engine is running and for a limited time after the engine has stopped, the circuit then being opened and remaining open until the engine is again started.

Lengthy experiments have demonstrated that this object may be achieved by utilizing the suction strokes of the engine to create a partial vacuum in a suitably shaped vessel provided with a diaphragm arranged so that the peripheral edge is fixed whilst the central portion is free to move in a direction at right angles to the plane thereof, a hinged switch or contact arm being connected to the diaphragm so that the movement of the latter will open and close the ignition circuit, and inserting a leaky or escape valve in the pipeline between the engine manifold intake and the vacuum chamber, or in the chamber itself, so that the vacuum created will be temporarily maintained.

In the accompanying drawing:

The figure is a central sectional elevation showing one method by which our invention may be carried into effect.

According to the construction shown in the drawing, a metal vacuum chamber 10 is fixed to any part of the chassis or any other convenient fixture in any appropriate manner, and is provided with a central aperture 11 through which it is connected by a pipe 11a to the engine manifold intake. Seated upon the top of the vacuum chamber is a discal diaphragm 12 which may be made of thin sheet celluloid or metal, or it may be of

leather of a suitable thickness, such diaphragm 12 being surmounted by a disc 14, preferably of fibre. A bolt 13 is passed upwardly through a central aperture in the diaphragm 12 which is secured to the underside of the head 13a so as to make an air tight joint. The bolt 13 also passes through a central aperture in the fibre disc 14 and thence through another aperture in the central member of a U shaped frame 15, which is secured to the fibre disc 14 by the bolts 16 and nuts 16a, the heads of the bolt 16 being countersunk in order that they will lie flush with the underside of the disc 14. The peripheral edges of the discs 12 and 14 are clamped tightly in position upon the chamber 10 by means of a flanged ring 17 which is internally screw threaded (18) to engage with an external screw thread 19 on the chamber 10.

The disc 14 serves as an insulating medium to insulate the U shaped switch carrying frame 15, whilst it also protects the diaphragm 12 against any possibility of being damaged by back pressure caused by back fire. The upper end of one of the side members of the frame 15 has a contact carrying arm 20 hinged thereto at 21, the other side member being provided with a terminal 22 that is secured to a block of electrical non-conducting material 23 which is secured to the frame 15 by the screw 24. The side member of the frame 15 which carries the contact carrying arm 20 is also provided with a terminal 25 which is screwed directly into the side member. The terminals 22 and 25 are for the purpose of enabling the switch frame to be inserted in the ignition circuit, a lead wire 26 from the electric battery being connected to one of the terminals 22 whilst the other lead 26a connects the high tension coil to the other terminal 25.

The hinged arm 20 is provided with a contact piece 27, the other contacting piece 28 being secured in position by and in electrical connection with the terminal 22. It will be of such a length that as it is moved downwardly upon its hinge the contact pieces 27 and 28 will be brought into electrical contact with one another and thereby close the elec-

trical circuit. The screw threaded end of the bolt 13 passes upwardly through an aperture in the hinged arm 20 and is provided with a nut 29 and lock nut 30 so that the movement 5 of the hinged arm 20 may be adjusted. The rear end of the hinged arm 20 is provided with an extension 20a, the outer end of which is connected to one end of a spring 31 the other end of which is connected by any suitable means to the adjacent side member of the frame 15. The spring 31 being held in tension between the side member of the frame 15 and the extension 20a the hinged arm is normally held in a raised position, its upper 15 face then abutting against the underside of the nut 29. In this position a space will exist between the contact pieces 27 and 28 and the electrical circuit will therefore be open.

In operation each suction stroke of the 20 engine will create a partial vacuum in the chamber 10 thereby causing the diaphragm 12 to belly downwardly and in doing so it will carry with it the bolt 13 and hinged arm 20 thereby bringing the contact pieces 27 and 25 28 together and closing the electrical ignition circuit. When the engine is stopped the pressure within the chamber 10 will return to normal or atmospheric pressure and the diaphragm will be permitted to return to its 30 normal flat shape, the spring 31 assisting such return by raising the hinged arm 20, nuts 29 and 30 and the bolt 13 to which the nuts are attached.

The switch frame 15 is enclosed within a 35 removable metal cover 32 which fits neatly over the flanged ring 17 and may be secured in position by set screws 33, or any other suitable means. The cover 32 will be provided with an aperture 32a through which the 40 leads 26 and 26a may pass.

The appliance as above described has been 45 found to give excellent results for general purposes, but when the speed of the engine is reduced below a certain point there is a tendency for the contact arm 20 to chatter. This is overcome by inserting a leaky or escape valve, preferably of the ball type, in the pipe line 11a or it may be located within 50 the chamber 10, as shown in the drawing in order to temporarily maintain the partial vacuum within the chamber and thus prevent the contact arm 20 from being actuated by its spring 31 in the interval between the 55 suction strokes of the pistons of the engine, the partial vacuum causing the contacts 27 and 28 to be held together and thus maintain a closed circuit through the leads 26 and 26a as hereinbefore described.

The escape valve as shown in the drawing 60 consists of a body part 34 having at one end thereof a short cylindrical shaped boss 35 which forms a shoulder 35a and screw threaded nipple 36. Passing through the body 34 and axially through the nipple 36 65 is a cylindrical passage 37, and at the end of

the body opposite the nipple 36 is a shallow recess 38 which is covered by a screw cap 39. The body part 34 will be located within the vacuum chamber 10, the shoulder 35a resting upon the bottom thereof and the boss 35 70 projecting into the central aperture 11 so that the body part may be secured in position by the nut 35b. For convenience the body part 34 may be circular in cross section and T shaped in vertical section so that by 75 boring and counterboring another hole 40 axially parallel with the passage 37 internal communication can be established between the chamber formed by the shallow recess 38 and the vacuum chamber 10.

The bottom of the counterbored portion of the hole 40 forms a leaky or imperfect seating for a ball 41 which will be caused to rise from the seating by the suction strokes of 80 pistons of the engine thus permitting the air within the chamber 10 to be partly exhausted but will fall again onto the seating, thereby closing the passage 40 and either maintaining a partial vacuum in the chamber 10 until air 85 has leaked between the ball and its seating from the engine manifold intake through the pipe 11a, passage 37, chamber or recess 38 the passage 40 to the chamber 10 sufficiently to destroy the vacuum in the latter, or until it is again raised from the seating by the next 90 suction stroke of any of the pistons of the engine which would increase the vacuum within the chamber 10. Any suitable packing 95 may be used to form air tight joints between the screw cap 39 and the body 34 and also between the body 34 and the chamber 10, and the distance between the underside of the cap 39 and the bottom of the recess 38 should be less than the diameter of the ball 41.

It will be obvious that the principle of the 105 invention could be applied to other constructions in order to operate an electric switch in the desired manner, but although we have tested several other methods the appliance herein described and illustrated in the accompanying drawing has given the most perfect 110 results.

We claim:—

A device of the class described comprising 115 a vacuum chamber connected by a pipe to the manifold intake of an internal combustion engine, an escape valve adapted to temporarily maintain a vacuum created within the chamber, said valve comprising a body including a chamber, a removable cap closing 120 the chamber, two passages through the body, both communicating with the chamber of the body, one passage establishing communication between the pipe and body of the chamber, the other passage establishing communication between the chamber in the body and the vacuum chamber, the latter passage having an imperfect seat therein, a ball valve 125 cooperative with the seat, means for securing the valve within the vacuum chamber, and 130

means for connecting the pipe to the body of
the valve.

In witness whereof we have signed this
specification.
